UNITED STATES PATENT OFFICE.

JOHN H. VINTON, OF JAMAICA PLAIN, MASSACHUSETTS, ASSIGNOR TO TRIMONT MANUFACTURING COMPANY, OF BOSTON, MASSACHUSETTS, A CORPORATION OF MAINE.

DESIGN FOR A HOUSING FOR WRENCHES.

42,343.

Specification for Design.

Patented Mar. 19, 1912.

Application filed October 30, 1911. Serial No. 657,614. Term of patent 14 years.

To all whom it may concern:

Be it known that I, JOHN H. VINTON, a citizen of the United States, residing at Jamaica Plain, county of Suffolk, State of Massachusetts, have invented a new, original, and ornamental Design for a Housing for Wrenches, of which the following is a specification, reference being had to the accompanying drawing, forming part thereof.

Figure 1 of the drawing is a perspective view of the housing for wrenches showing

my new design; Fig. 2 is a perspective view thereof from the opposite end; and Fig. 3 is an end elevation of the housing for wrenches showing my new design.

I claim:

The ornamental design for a housing for wrenches, as shown.

JOHN H. VINTON.
